Int. Cl. D3—99

U.S. Cl. D87—1 R

FIG. 1

FIG. 2

Des. 234,378

PAGE 2

~~FIG.~~ 3

~~FIG.~~ 4

FIG. 5

FIG. 6

FIG. 1 is a front elevational view of a case for a sewing machine showing my new design;

FIG. 2 is a rear elevational view;

FIG. 3 is a top plan view;

FIG. 4 is a bottom plan view;

FIG. 5 is an end elevational view looking from the right of FIG. 1;

FIG. 6 is an end elevational view looking from the left of FIG. 1; and

FIG. 7 is a perspective view thereof.

I claim:

The ornamental design for a case for a sewing machine, as shown.
